C. E. LINDSAY

TRACK LINING JACK

Filed June 3, 1921

Patented Mar. 18, 1924.

1,487,393

UNITED STATES PATENT OFFICE.

CHARLES E. LINDSAY, OF ALBANY, NEW YORK.

TRACK-LINING JACK.

Application filed June 3, 1921. Serial No. 474,663.

To all whom it may concern:

Be it known that I, CHARLES E. LINDSAY, a citizen of the United States, residing at Albany, in the county of Albany and State of New York, have invented certain new and useful Improvements in Track-Lining Jacks, of which the following is a specification, reference being had therein to the accompanying drawing.

10 My invention relates to a track lining jack and I declare the following to be a full, clear, concise and exact description thereof sufficient to enable anyone skilled in the art to which it appertains to make 15 and use the same, reference being had to the accompanying drawings in which like reference characters refer to like parts throughout the specification.

The object of the invention is to provide 20 a device that can be operated by a single person for alining a railroad track.

The object will be understood by referring to the drawings in which:

Fig. 1 is a side elevation of the device 25 shown in connection with a railroad track, which is in section;

Fig. 2 is a rear end view of the device, showing parts in section.

Fig. 3 is a detail view, showing the 30 ratchets and spur gear, employed, mounted on a sleeve that is carried by a shaft, also a pulley carried on a shaft suspended from hangers mounted on said sleeve, certain of the above parts being illustrated in section;

Fig. 4 is a detail view of a clevis and pin 35 employed.

Referring more particularly to the drawings, the device embodies a push rod —1— which has formed thereon at its free end 40 a gear rack 2 adapted to mesh with the spur gear 3 that is formed integral with a hollow shaft or sleeve 4 mounted to turn on a stationary shaft 4^a, the reduced ends of which shaft 4^a are carried in lugs 5, 5.

45 Said ends are threaded also for the reception of nuts 4^b. The lugs 5 are formed integral with the upper parts of the blades or scoops 6, 6, which are adapted to be firmly embedded in the ballast or roadbed.

50 Laterally projecting ribs 7, 8 and 9, are made integral with each of the blades 6, whereby to aid in holding the same firmly in the ballast or roadbed.

55 The rack 2 is supported at its free end by a roller 10 that is mounted to turn upon a shaft 11 carried by hangers 12, 12. The

hangers 12 are supported at their upper ends on the hollow shaft or sleeve 4 from which they are suspended. The roller 10 also is adapted to hold the gear rack 2 in 60 mesh with the spur gear 3.

There is mounted on the square parts 15^a, 15^a of the rotatable sleeve 4, two ratchet wheels 15, 15, which are held in place on said hollow shaft 4 by collars 16 and set 65 screws 17, 17. Said collars 16 and set screws 17 also hold the sleeve 4 in place on the shaft 4^a. The teeth of each of these ratchets 15 is engaged by a drive pin 18. The drive pins 18, 18 are screw mounted in each instance to one of the forks 19 of a yoke 20. The yoke 20 is connected by screw mounting the same to the lower end of a rod 22. The drive pins 18 are held yieldingly in engagement with the teeth of the ratchets 15 70 respectively by coiled springs 21, 21 connecting rod 22 with rods 32, 32. A U shaped pawl rod 34 having its free ends pivotally connected to the projecting parts 35, 35 of the clamps 36, 36 is adapted to engage in 75 a yielding manner also the teeth of the ratchets 15, 15, whereby to hold said ratchets 15 from turning in the reverse direction, when the drive pins 18 move over the teeth to engage succeeding teeth.

80 The upper end of rod 22 is fulcrumed at 23 to one end of a lever receiver or socket 25, which is adapted to hold in a removable manner the handle 25^a. The lever receiver or socket 25 is fulcrumed in 85 its turn upon a shaft 26 that is supported in bearings 30, 30 formed in clamps 31, 31. The clamps 31 are mounted in each instance upon the rods 32, 32. The shaft 26 is supported also by the hanger yoke 33, the upper end of which is screw mounted to a rod 37 that is fulcrumed upon a shaft or apex pin 38. The pin 38 is held to assembled position by cotter pins 38^a, 38^a. The upper ends of the rods 32 are pivoted 90 also upon said shaft or pin 38. The lower ends of rods 32 are fastened to the blades or scoops 6.

95 The bearing ends 40, 40 of a clevis 41 are mounted upon the shaft 38 and disposed between the bearings of the rods 37, 32, 32. A rod 42 is fastened at one end to the clevis or U-shaped member 41 and at the other to another clevis or U-shaped member 46. A headed pin 45 is adapted to be projected 100 through aligned openings formed in the forks 46^a, 46^a of the clevis 46 and an opening 110

formed in the head socket 50, whereby to hold said parts together in a removable manner. The head socket member 50 is equipped with an opening 47 adapted to engage the base portion 48 of a rail 49. The push rod —1— is fastened also to the head socket member 50 at 51.

The operation is effected by placing the device in its proper position with relation to a railroad track to be alined, whereby the opening 47 will engage the base 48 of the rail and the blades 6 be disposed in the ballast or roadbed a short distance from said rail. The gear rack 2 will be disposed with its upper end under the spur gear 3. By now bearing down on the outer end of handle 25^a, the drive pins 18, 18 will be elevated through their connections by means of rod 22 and yoke 20, whereby to rotate ratchets 15, 15 a partial revolution. The rotation of ratchets 15 will effect a partial rotation of spur gear 3, which is adapted to turn therewith and, hence, actuate the gear rack 2 towards the rail at an angle thereto, whereby to give the required vertical and lateral movement necessary to loosen the rail and tie 52 in the ballast and shift the same laterally to the required distance. As the drive pins 18 ride over the teeth of their respective ratchets 15, said ratchets will be held from turning in the reverse direction by the pawl rod 34, which drops down by gravity to engage each succeeding tooth of the respective ratchets 15, 15.

In the event it is found desirable to remove the upstanding parts of the device quickly, as upon the sudden approach of a train, the headed pin 45 can be removed from its position, namely that of joining the clevis 46 and head socket 50 together and, then, the upstanding parts can be withdrawn out of the way quickly.

The handle 25^a can be withdrawn from its socket 25 at the will of the user.

It will be noted that the track lining jack translates the downward movement of lever

25^a into an approximately horizontal movement of the push bar 1, which motion is best adapted to stabilize the track lining jack for effecting the desired result.

Having thus described my invention what I claim as new and desire to secure by Letters Patent is:

1. In a track lining jack, a head socket having an opening for engaging the base of a rail, a gear rack connected with said head socket, a gear in mesh with said rack, ratchet wheels mounted to turn with said gear, drive pins engaging the teeth of said ratchet wheels, and means for actuating said drive pins, whereby to actuate the several parts for moving a rail.

2. In a track lining jack, a head socket having an opening for engaging the base of a rail, a gear rack connected with said head socket, a gear in mesh with said rack, ratchet wheels mounted to turn with said gear, drive pins engaging the teeth of said ratchet wheels, a lever intermediately connected with said drive pins, whereby to actuate the several parts to move a rail, and means for holding said ratchets in given position of rotation.

3. In a track lining jack, a head socket having an opening for engaging the base of a rail, a gear rack connected with said head socket, a gear in mesh with said rack, means mounted to turn with said gear, drive pins engaging said means, and other means for actuating said drive pins, whereby to actuate the several parts for moving a rail.

4. In a track lining jack, means for engaging the base of a rail, a gear rack connected with said means, a gear in mesh with said rack, ratchet wheels mounted to turn with said gear, drive pins engaging said ratchet wheels, and means for actuating said drive pins, whereby to actuate the several parts for moving a rail.

In testimony whereof I have affixed my signature.

CHARLES E. LINDSAY.
